TRANSLOAD DEVICE

Alan E. Brickman, Williamsville, N. Y., assignor to United States Steel Corporation, a corporation of New Jersey

Application October 20, 1954, Serial No. 463,539

5 Claims. (Cl. 94—8)

This invention relates to a transload device and more particularly to such a device for use in pavement joints, concrete highways, airport runways and the like. Such a device is shown in my prior Patent No. 2,674,164, dated April 6, 1954. While the patent shown therein is satisfactory in operation it has the disadvantage of not being easily stacked for shipment in trucks which is the common way of shipping transload devices.

It is therefore an object of my invention to provide a transload device which is easily assembled and which can be arranged in nested position for shipment without danger of damage thereto.

This and other objects will be more apparent after referring to the following specification and attached drawings, in which:

Figure 1 is a perspective view of an expansion joint assembly;

Figure 2 is a transverse section of the expansion joint of Figure 1;

Figure 3 is a view taken on the line III—III of Figure 1;

Figure 4 is an enlarged sectional view of a detail;

Figure 5 is a view of a plurality of units stacked for shipment; and

Figure 6 is a view, similar to Figure 2, but showing a contraction joint.

Referring more particularly to the drawings, reference numeral 2 indicates a pair of concrete slabs having the usual filler member 4 therebetween. My device may be made of two complementary units which are telescoped together. Each unit has two longitudinal rods 6 and 8 spaced from the filler 4 and connected by rods 10 and 12. The lower end of the rod 10 is welded to the bottom longitudinal rod 6 and extends upwardly and outwardly therefrom and then inwardly to form a knee 13. From the knee 13 the rod 10 extends upwardly above the rod 8 to which it is welded. The part of the rod 10 above the rod 8 is U-shaped, thus providing an opening 14 for receiving a dowel 18 which is welded to the rods 8 and 10. The lower part of the rod 12 is shaped in the same manner as the rod 10, that is, it extends upwardly and outwardly from the rod 6 to which it is welded and then inwardly to form a knee 19 and then upwardly to the rod 8 to which it is welded. The upper part of the rod 12 forms a clamping device 20 which is provided with a loop 22 for receiving the free end of the dowel 18 and a longitudinal portion 24 which extends along the rod 8. The free end of the portion 24 has a hook 26 which is adapted to pass below and extend around the rod 8 to a point just below the axis of the rod. The rods 10 and 12 are arranged alternately with the rods 10 of one unit being opposite rods 12 of the other unit. A plate 28 is welded to each of the dowels 18 on that side of the filler 4 adjacent the rod 10. Plate 28 extends between the dowels 18 and is provided with corrugations 30. Holes 32 are provided in the plate 28 between the dowels 18 for receiving the dowels of the other unit. Holes 34 are provided in the filler 4 for passage of the dowels. The free ends of the dowels have a sleeve 36

2

telescoped thereover with an expansible filler 38 being provided in the sleeve 36 at the outer end thereof, as shown in Figure 4.

In assembly, the two units are brought together by passing the free ends of the dowels through the openings 34 into the loops 22. The sleeves 36 and fillers 38 are then applied to the dowels and the hook 26 is moved from the dotted line position of Figure 3 to the full line position, thus locking the two units together with the plates 28 bearing against opposite sides of the filler 4 to hold it in position while concrete is poured. The plates 28 do not interfere with the flow or packing of the concrete around the dowels adjacent the joint, thus making it possible to provide dense concrete at the most critical places.

15 The device functions in the usual manner as the concrete slabs 2 expand and contract.

In shipment the assembled units with the fillers 38 and sleeves 36 removed are nested together as shown in Figure 5. As there shown the dowels 18 of the lowest unit are supported on wooden skids 40 which are of sufficient height that the unit is supported solely on the skids. The longitudinal rods 6 of the next unit are supported by the knees 13 and 19. The height of the plates 28 is less than the vertical distance between the knees and the bottom longitudinal rod 6 so that the top parts of the plates of one unit are below the bottom of the plates of the next unit above.

20 Figure 6 shows my device as applied to a contraction joint. This joint differs from the expansion joint in that the plates 28, sleeves 36 and filler 38 are omitted and a steel separating plate 42 is substituted for the expansible filler 4.

25 While several embodiments of my invention have been shown and described it will be apparent that other adaptations and modifications may be made without departing from the scope of the following claims.

I claim:

1. In a transload device for adjacent slabs having a filled therebetween, the combination including a pair of telescoping supporting units, one positioned on each side of the filler, each unit comprising a pair of outboard longitudinal rods spaced apart one above the other, spaced apart rods extending between and welded to said longitudinal rods, each of said last named rods extending upwardly and outwardly from said bottom rod, then inwardly to form a knee at a point intermediate the top and bottom rods and then upwardly to the top rod, a dowel fastened to each of said last named rods, the spacing between opposed bottom longitudinal rods being at least approximately as great as the length of said dowel, a plate welded to each of said dowels adjacent said filler, a clamping rod between adjacent pairs of said last named rods extending between and welded to the bottom and top longitudinal rods in opposed relationship to the second named rods associated with the opposite pair of longitudinal rods, said clamping rod having a loop extending above said top longitudinal rod and clamping the free end of the dowel secured to said opposed rod, each of said clamping rods extending upwardly and outwardly from said bottom rod, then inwardly to form a knee at a point intermediate the top and bottom rods and then upwardly to the top rod, the knees associated with each pair of outboard longitudinal rods being in alignment and forming a support for the bottom longitudinal rod of a second transload device when arranged in nested position.

2. In a transload device for adjacent slabs having a filler therebetween, the combination including a pair of telescoping supporting units, one adapted to be positioned on each side of the filler, each unit comprising a pair of outboard longitudinal rods spaced apart one above the other, spaced apart rods extending between and welded

to said longitudinal rods, each of said last named rods extending upwardly and outwardly from said bottom rod, then inwardly to form a knee at a point intermediate the top and bottom rods and then upwardly to the top rod, said knees forming a support for the bottom longitudinal rod of a second transload device when arranged in nested position, each of said last named rods having a U-shaped upper portion extending above the upper longitudinal rod to form an opening, a dowel passing through each opening and welded to the walls thereof, a plate welded to each of said dowels and adapted to bear against one side of said filler, said plate having a vertical height less than the vertical distance between said knee and the bottom longitudinal rod, a clamping rod between adjacent pairs of said U-shaped rods extending between and welded to the bottom and top longitudinal rods, each of said clamping rods extending above the top longitudinal rod and having a loop receiving a dowel of the opposite unit, each of said clamping rods extending from said loop along said top longitudinal rod and having a hook portion at the free end which passes below and around the top longitudinal rod, each of said clamping rods extending upwardly and outwardly from said bottom rod, then inwardly to form a knee at a point intermediate the top and bottom rods and then upwardly to the top rod, said knees forming a support for the bottom longitudinal rod of a second transload device when arranged in nested position.

3. In a transload device for adjacent slabs, the combination including two pairs of outboard longitudinal rods, one pair on each side of the joint between the slabs, the rods in each pair being spaced apart one above the other, dowels spaced apart in parallel relationship extending between and supported by the upper longitudinal rods, the spacing between opposed bottom longitudinal rods being at least approximately as great as the length of said dowel, spaced apart rods extending between and welded to the longitudinal rods of each pair, each of said last named rods extending upwardly and outwardly from its associated bottom rod, then inwardly to form a knee at a point intermediate its associated top and bottom rods and then upwardly to the top rod, the knees associated with each pair of outboard longitudinal rods being in alignment and forming a support for the bottom longitudinal rods of a second transload device when arranged in nested position.

4. In a transload device for adjacent slabs, the combination including two spaced pairs of outboard longitudinal rods, the rods in each pair being spaced apart one above the other, spaced apart rods extending between and welded to the longitudinal rods of each pair, each of said last named rods extending upwardly and outwardly from its associated bottom rod, then inwardly to form a knee at a point intermediate its associated top and bottom rods and then upwardly to the top rod, a dowel extending between said top longitudinal rods, the spacing between opposed bottom longitudinal rods being at least approximately as great as the length of said dowel, a sub-

stantially vertical plate welded to said dowels intermediate the length thereof, a clamping rod between adjacent pairs of said second named rods having a vertical portion extending between and welded to the bottom and top longitudinal rods in opposed relationship to the second named rods associated with the opposite pair of longitudinal rods, said clamping rod having a loop extending above said top longitudinal rod and clamping one end of said dowel, the other end of said dowel being secured to said opposed rod, each of said clamping rods extending upwardly and outwardly from said bottom rod, then inwardly to form a knee at a point intermediate the top and bottom rods and then upwardly to the top rod, the knees associated with each pair of outboard longitudinal rods being in alignment and forming a support for the bottom longitudinal rod of a second transload device when arranged in nested position.

5. In a transload device for adjacent slabs, the combination including two spaced pairs of outboard longitudinal rods, the rods in each pair being spaced apart one above the other, spaced apart rods extending between and welded to the longitudinal rods of each pair, each of said last named rods extending upwardly and outwardly from its associated bottom rod, then inwardly to form a knee at a point intermediate its associated top and bottom rods and then upwardly to the top rod, said spaced apart rods having a U-shaped upper portion extending above the upper longitudinal rod to form an opening, a dowel passing through each opening and welded to the walls thereof, the spacing between opposed bottom longitudinal rods being at least approximately as great as the length of said dowel, a substantially vertical plate welded to said dowels intermediate the length thereof, a clamping rod between adjacent pairs of said U-shaped rods having a vertical portion extending between and welded to the bottom and top longitudinal rods in opposed relationship to the second named rods associated with the opposite pair of longitudinal rods, said clamping rod having a loop extending above said top longitudinal rod and clamping the free end of the dowel secured to said opposed rod, each of said clamping rods extending upwardly and outwardly from said bottom rod, then inwardly to form a knee at a point intermediate the top and bottom rods and then upwardly to the top rod, the knees associated with each pair of outboard longitudinal rods being in alignment and forming a support for the bottom longitudinal rod of a second transload device when arranged in nested position.
